UNITED STATES PATENT OFFICE.

WAYNE A. PERKINS, OF HAWTHORNE, NEVADA.

PANTOGRAPHIC APPARATUS FOR ATTACHING TO UNIVERSAL DRAFTING MACHINES.

1,415,695.

Specification of Letters Patent.

Patented May 9, 1922.

Application filed April 30, 1920. Serial No. 377,871.

To all whom it may concern:

Be it known that I, WAYNE A. PERKINS, a citizen of the United States of America, residing at Hawthorne, in the county of Mineral and State of Nevada, have invented certain new and useful Improvements in pantographic apparatus for attaching to universal drafting machines, for copying, reducing, and enlarging drawings; and I do hereby declare the following to be a full, clear, and exact description of the invention, such as will enable others skilled in the art to which it appertains to make and use the same.

The principal object of my invention is to provide an attachment for use in combination with the well known universal drafting machine, which attachment may be used in the same manner as the ordinary pantograph but with increased latitude and usefulness due to the adjustable hinged arms and other features hereinafter described.

Another object of my invention is to provide an attachment for use in combination with the well known universal drafting machine consisting of parallel pairs of arms by which the range of the relative positions of the two or more drawings can be greatly increased beyond that provided by the single arms, which in conjunction with adjustable pencil or tracing point holder give further increased latitude and usefulness.

Further objects of the invention are to provide a device of this class which shall possess superior advantages in point of simplicity, general efficiency, and may be used as a pantograph or drafting machine as desired.

The invention consists of adjustable arms pivotally hinged together with opposite ends attached by means of yokes and clamps to the parallel arms of the drafting machine, with provision for clasping a pencil or tracing point at the center of the circular hinge and a holder arm inserted in the usual head of the drafting machine carrying an adjustably attached holder for a pencil or tracing point.

The invention also consists of two pairs of parallel adjustable arms pivotally clamped to a ring by means of set screws, with opposite ends of said arms attached by similar means to the parallel arms of the drafting machine, with an extension holder arm pivotally inserted in the ring carrying

an adjustable pencil or tracing point holder, in combination with a similar holder arm inserted on the protractor head of the drafting machine, also carrying an adjustable pencil or tracing point holder.

The invention further consists in the combination with the drafting machine of the improved construction, arrangement and combination of parts which will be herein-after fully described in the specification and particularly claimed.

With these and other ends in view, which will readily appear as the nature of the invention is better understood and used, I will proceed to describe its construction and operation, reference being had to the annexed drawing, in which,

Figure 1 is a plan view of the pantographic device attached to the universal drafting machine.

Fig. 2 is a plan view of a modification of the apparatus.

Fig. 3 is a side elevation of the apparatus on line 1—1 of Fig. 1.

Fig. 4 is a side elevation of the apparatus on line 2—2 of Fig. 2.

In the drawing similar reference characters refer to the same part in all the views; the parts of the universal drafting machine are referred to by letters and the parts of the device more particularly described and claimed separately and in combination with said universal drafting machine are shown by figures.

Referring to the drawing, the device is more particularly described as consisting of two arms 5 and 7, Fig. 1, adjustable in length, attached by pivoted clamps 4 and 8 respectively to yokes 3 and 9 respectively, with a cylindrical ring joint at 6. Yokes 3 and 9, Fig. 1, in turn are attached by pivoted clamps 1, 2, 10 and 11 respectively to arms A, B, C, and D respectively of the universal drafting machine, shown with broken lines. It also consists in combination with the universal drafting machine of holder arm 14 inserted in scale holder F of the drafting machine, on which is provided holder 12 attached to holder arm 14 by set screw 13, constructed to hold a pencil or tracing point when in use. Circular ring joint 6 is provided with a hole in the center thereof in which may be inserted a pencil or tracing point when in use.

It is noted that clamps 1 and 2 as illustrated in Figs. 1 and 3 are attached to arms

A and B at a point where the ratio of the distance from bolt a to clamp 1, and bolt a^1 to clamp 2 is to the length of arms A and B as the scale of the smaller drawing is to 5 the scale of the larger drawing, and the distance from bolts a^4 and a^5 to clamps 10 and 11 are made equal to the distance from bolt a to clamp 1 and bolt a^2 to clamp 2 respectively. The length of arm 5 is set equal to 10 the distance from bolt a at inner end of arm A to clamp 1 or the distance from bolt a^4 to clamp 10, and the length of arm 7 is set equal to the distance from bolt a^1 to clamp 1 thus forming a parallelogram. By 15 the additional circular movement obtainable through use of protractor head N a much greater latitude in the relative positions of the two drawings is permitted than is obtainable with the ordinary pantograph. 20 When properly set it is seen that any movement of protractor head N or the pointer holder 12 will produce a similar movement of the pencil or tracing point at 6, the amount of the latter being in the same ratio 25 to the movement of pointer holder 12 as the length from bolt "a" on inner end of arm A to clamp 1 is to the length of arm A.

An important modification of my invention will now be described. This modification 30 consists in the use of two pairs of parallel arms as illustrated in Figs. 2 and 4. The principle of the modification is the same as in the use of single arms, but by the use of two pairs of arms 15, 16, 17 and 18 in 35 place of single arms 5 and 7, the circular yoke 19 will always be held in a position parallel to itself and the range of the relative positions of the two drawings on which the device is being used can be greatly increased 40 beyond that accomplished by the device illustrated in Figs. 1 and 3. This is accomplished by the use of pencil or tracing point holder 21 adjustably attached by means of set screw 23 to arm 22. Arm 22 45 is in turn pivotally attached by means of set screw 20 to circular yoke 19, Fig. 2, and so clamped in any desired position. Arms 15 and 16, Fig. 2 are pivotally attached to circular yoke 24 by clamps 25 and 26, and 50 circular yoke 24 is pivotally clamped to arms A and B by clamps 1 and 2. Arms 17 and 18, Fig. 2 are pivotally attached to circular yoke 27 by clamps 28 and 29, and circular yoke 27 is in turn pivotally clamped to arms 55 C and D by clamps 10 and 11. Arms 15, 16, 17, and 18 are pivotally attached to circular yoke 19 by means of clamps 30, 31, 32, and 33 respectively, as is shown in Figs. 2 and 4.

In the operation of this modified device 60 as shown in Figs. 2 and 4, the same use is made of it as hereinbefore described, except that in place of the single arms 5 and 7, the pairs of arms 15 and 16, and 17 and 18 must each be set equal to the distance from bolt a^4 to clamp 10, and bolt a^5 to clamp 11,

and from bolt a^1 to clamp 1 and bolt a^3 to clamp 2 respectively. This modified device may be caused to perform work in any position in which it is placed and setting proper proportions only is essential to its effective 70 working.

The universal drafting machine with which this is necessarily made in combination consists of a frame composed of four arms or bars A, B, C, and D, Figs. 1 and 3. 75 One end of arm A is pivoted to anchor O by means of bolt or screw "a", or other suitable means, the other end being pivoted to ring M by means of similar bolt a^1 . The ends of parallel arm B are similarly pivoted to anchor O and ring M by bolts a^2 and a^3 respectively. Anchor member O is provided with a set screw P for attaching the device to any drawing table or other appropriate support. Arms C and D are each pivotally attached 80 to ring M by means of bolts a^4 and a^5 respectively at one end and the other end is similarly attached to holder frame E by means of bolts a^6 and a^7 respectively. Circular head or protractor N is attached to holder frame E by means of set screws b^1 and b^2 . Head N is provided with a scale holder arm F. Inserted on scale holder arm F is graduated scale arm 14, which carries adjustable holder 12 clamped securely thereto by means 85 of set screw 13, Fig. 1, which is provided with a hole for insertion of pencil.

Various modification of this device within the scope of the invention and defined in the following claims may be made in the 100 particular construction of the device, and also in the shape and organization of the active members thereof without departing from the spirit of this improvement.

I am aware that the parallel arms or 105 motions of the universal drafting machine and the ordinary pantograph are not new, but it will be noted that the principles of the universal drafting machine and the ordinary pantograph are combined in a novel manner 110 and so arranged as to be capable of being used as either or both, so I do not claim such a combination as described broadly, but having described my invention, what I claim as new and desire to secure by Letters Patent 115 is—

1. An attachment for a drafting machine having pivotally connected arms, comprising two arms pivotally connected to each other and having their free ends adapted to 120 be pivotally secured to the arms of said machine, and means for securing a marking instrument to the pivotal connection between said arms, substantially as described.

2. An attachment for a drafting machine 125 having pivotally connected arms, comprising two arms pivotally connected to each other and having their free ends adapted to be pivotally secured to the arms of said machine, each of said two arms including a pair 130

of parallel rods, a yoke pivotally connecting the ends of one pair of rods to the other, and yokes for pivotally connecting the free ends of said arms to the arms of said machine, a graduated scale arm adapted for attachment to said first mentioned yoke, a device for holding a marking instrument mounted on said scale arm, and means for securing same thereto, substantially as described.

3. In combination a pantographic device comprising a stationary base, a pair of pivotally connected arms, a yoke pivotally connected to said arms, a second pair of pivotally connected arms attached to said yoke, a protractor head device pivotally connected to the free end of said second pair of arms, a graduated scale arm attached to said protractor head device, an adjustable marking

holder mounted on said scale arm, a third and fourth pair of pivotally connected arms, a second yoke carrying said third and fourth pair of arms, a third and fourth yoke respectively pivotally attached to said first and second pair of arms carrying respectively attached thereto said third and fourth pair of arms, a graduated scale arm attached to said second yoke, an adjustable pencil holder member mounted on said scale arm, and set screw means for holding said parts in adjustable positions, as and for the purpose described.

In testimony whereof I affix my signature in the presence of two witnesses.

WAYNE A. PERKINS.
